MATERIAL HOLDER FOR DRILLING

Freeman C. Foss, Twin Falls, Idaho

Application December 14, 1948, Serial No. 65,096

2 Claims. (Cl. 77—63)

1

This invention relates to novel and useful improvements in attachments for drill presses and similar devices.

An object of this invention is to provide an improved attachment for use in holding firmly for drilling any material such as flat, irregular or straight edged, round stock and other material of different shapes.

At present there is utilized various devices for performing similar functions of the present device. There are used jigs, iron blocks, wooden blocks, specially devised brackets, drilling vises. However, in practical use a large part of the holding of metal for drilling is attempted to be done by hand, that is with a pair of pliers or some other similar mechanism. It has been found that such type of drilling is not only dangerous but inaccurate and tends to ruin drill bits as well as the very stock which is being drilled.

Hence, it is another prime object of this invention to retain a workpiece, whether it be round, square, irregularly shaped or the like in a manner whereby accurate and safe holes or other cutting operations may be performed thereon, without the necessity of large, expensive and cumbersome holding devices.

Ancillary objects and features of novelty will become apparent in following the description of the preferred form of the invention and certain of its various uses, as the description of the drawings proceed, wherein:

Figure 1 is a plan view of the preferred form of the invention;

Figure 2 is an elevational view of the device shown in Figure 1, portions being broken away in section to illustrate details of construction;

Figure 3 is a front view of the holder portion of the device;

Figure 4 is a perspective view of the device, showing the same in use on a drill press, and;

Figure 5 is a perspective view somewhat similar to that shown in Figure 4, showing the attachment utilized in connection with a different piece of stock.

The structure to be described is capable of holding various types of stock. As an example, certain holding operations have been selected for illustration in the drawings. However, other types of stock may be efficaciously held while being drilled to wit: the holding of a washer in order to enlarge the central aperture therein or in order to make a washer from a piece of stock. This is an extremely difficult operation due to the usually very small size of the washer. Of course, the capabilities of the apparatus are known only partially that is, for particular shops doing somewhat similar jobs repeatedly, the attachment may be adapted for holding certain parts, as in reaming bushings, removing bearing inserts etc.

The drill press indicated generally at 10 is of

conventional description and includes a table 12 with the usual column 14 as well as other pertinent mechanism.

The attachment in order to be commercially feasible must be simple in structure. Hence, there is included only a minimum of elements. A base block or base 16 is provided in substantially circular shape for convenience and has a lower flange portion 18. This lower flange portion has a slot 20 therein communicating with a slot 22 formed in the bottom of the base. The flange portion 20 and the slot 22 is used for accommodation of the holding screw 27 of the drill press. Hence, the block 16 may be maintained firmly in place for more-or-less heavy operations and also for repeated operations.

A through bore (unnumbered) is provided in the block 16 and accommodates a rod 26 which has an upturned end portion 28. This rod is adapted to serve as a gauge for performing successive operations on a piece of stock as that shown at 30. The stock having had one hole drilled therein after being center punched is disposed on the upturned end portion 28 (in the hole) thereby placing it with respect to the drill bit 32 and chuck member 34 in such a position so that a spaced second hole may be made therein at a predetermined distance from the first. If it is desired to make the holes successively in a piece of stock with more or less distance between the holes, it is only necessary to loosen the set screw 38 and slide the rod 26 in the bore for adjustability.

A hollow handle 40 extends from the block 16, being fixed thereto. This handle has a pair of threaded apertures 42 and 44 respectively which are aligned, therein for accommodation of a screw 46. It also has another aperture 48 therein accommodating the screw 50. These screws are of the holding type in order to firmly fix the holder generally indicated at 52 thereto.

This holder 52 has a threaded opening (unnumbered) at one end thereof accommodating the screw 50 with a suitable turning end member thereon. This is a tightener screw disposed at the end of the holder 52 so that it is spaced from the drill chuck and so that it is readily accessible. Manipulation of the screw 50 will pull the work retaining holder 52 against the stock and retain it firmly. The screw 46 has a nut 54 thereon in order to level the holder 52, being used particularly to adjust properly for different depths or thicknesses of stock.

A guide 58 is slidably disposed in a bearing 60 formed integral with or fixed rigidly to the base block 16. The said die is preferably an L-shaped member which is retained in selected adjusted positions in the bearing 60 by means of a set screw 62.

Another guide member which is preferably a

screw 64 is threadedly disposed in another bearing 66 also carried by the block 16. The screw 64 and guide 58 are slidably in substantial parallelism in order that the side of a piece of stock may be guided to spaced points.

If it is desired to remove the rod 26 and substitute it by means of another type of gauge or guide, this may be accomplished as shown in Figure 4. Here a substantially U-shaped rod 68 is illustrated with one leg disposed in the bore and the other leg is disposed on top of the base block 16. Hence, the piece of stock 70 is retained at the end thereof by means of this rod 68.

As discussed previously, the hold down screw 27 may be used to anchor the base or base block 16. Thus, it is also noted that the majority of work accomplished by the attachment in practical operation will be done while the device is being held manually. The handle 40 serves this purpose. On the other hand, if it is desired to permit the handle to simply strike the column 14 of the drill press, this may be done. The torque of the bit 32 will urge the handle firmly against the column.

The holder being bifurcated at one end thereby forms an opening for the passage of the drill bit 32. Another passage or opening 74 is provided in the base block 16 serving the same purpose.

The bifurcated end portion of the holder 52 is smoothly curved from the outside edges tapering downward toward the opening formed by furcations. Holding grooves 76 are provided in the under surface of each bifurcation adjacent the end thereof in order to clamp certain types of stock, such as the round stock schematically shown at 80. There is a flattened portion of the bottom of the bifurcations on each side of the grooves 76 for firmly clamping flat stock as that shown at 30 and 70.

The innermost back portion 82 between the bifurcations of the holder is dished downwardly and tapers slightly as shown in Figures 1 and 3 and tapers inwardly in order that a washer or other small article may be retained immediately thereunder so as to make the aperture in the washer larger or so as to actually form a washer from a small piece of stock.

Shoulders 86 and 88 respectively (see Fig. 3) are thick at the front and taper toward the back of the holder 52 toward the innermost back portion 82 between the bifurcations. The utility of this taper is such that it is high enough at the front and tapers downwardly toward the back in order to accommodate various sized bits so that the cutting lip of the conventional bits will not lap over on the holder 52 when seating the material for drilling. The tapering is such that an individual can and does have best vision at the back portion of the holder that is possible in order that the center punch mark commonly associated with drilling may be readily seen and yet not permit any of the bits of the necessary size to lap over.

When the holder 52 is rotated to a position somewhat similar to that shown in Figure 4 in order that the base may be used as a bench iron, the clamp 52 rests upon the bearings 60 and 66 respectively, balancing the holder. Hence, the bearings serve a dual function, that is to hold the members 66 and 68 and also to support the actual tool holder 52 under certain operative conditions.

The actual shape of the holder is of major importance in the present device, since it is by this shape that various types of stock may be held.

It is not infrequent that the flat bottom surface of the holder and the grooves 76 as well as other variously configured portions of the device are called into play in order to hold a single piece of stock.

While there has been described and illustrated but one form of the invention, it is apparent that variations may be made without departing from the spirit thereof. It is also understood that many uses may be made of the described structure such as coming within the purview of a skillful operator.

Having described the invention, what is claimed as new is:

1. A work-holding device for use with a drill press, said device comprising a block which is adapted to be secured to the table of the drill press, a work holder having furcations at one end thereof, an adjustment screw threaded in the opposite end thereof and contacting said block to raise and lower said holder with respect to the block, a pivot bolt carried by said block and passed through an opening in said holder intermediate its ends, a threaded element disposed on said pivot bolt and engaging said holder to press said holder downwardly toward the block to clamp a workpiece therebetween, said holder being pivotally operable to the operative and inoperative condition about the axis of said pivot bolt, said furcations having their upper surfaces downwardly and inwardly tapered from the inner ends thereof to the outer ends thereof and said furcations being tapered inwardly toward their inner ends said last-mentioned taper being with respect to vertical planes passed through said furcations, and means disposed in the under surface of said furcations to accommodate a workpiece.

2. A work holding device for use with a drill press, said device comprising a holder with furcations at one end, said furcations opening outwardly and tapered inwardly to a V-notch, the furcations being relatively thick at their outer ends to engage larger work, and tapered thinner toward the inner ends thereof, and the innermost portions of the furcations being dished downwardly and tapered inwardly to provide vision space near the V-notch during drilling operations, and said holder having a reduced width handle extending therefrom substantially parallel to said furcations.

FREEMAN C. FOSS.
